ELECTRIC TIME-INSTRUMENT SYSTEM

Walter W. Lunden, Hampden, Mass., assignor to
The Standard Electric Time Company, Springfield,
Mass., a corporation of Connecticut

Application February 4, 1942, Serial No. 429,451

5 Claims. (Cl. 58—24)

This invention relates to improvements in electric time-instrument systems in which one or more time-means are controlled by a master time-instrument.

One object of this invention is to provide an improved electric time-instrument system in which one or more time-means are so controlled in their timing and resetting phases from a master time-instrument that at least one of the time-means can be periodically corrected without ever running it backwards.

With the above and other objects in view, as will appear to those skilled in the art from the present disclosure, this invention includes all features in the said disclosure which are novel over the prior art.

In the accompanying drawings forming part of the present disclosure, in which certain ways of carrying out the invention are shown for illustrative purposes:

Fig. 1 is a front elevation of time-means made in accordance with the present invention;

Fig. 2 is a sectional view on line 2—2 of Fig. 1;

Fig. 3 is a sectional view on line 3—3 of Fig. 1;

Fig. 4 is a perspective view of the reset-cam and the minute-timing cam;

Fig. 5 is a perspective view of the one-way driven cam;

Fig. 6 is a schematic view illustrating one way of carrying out the present invention; and

Fig. 7 is a schematic view similar to Fig. 6 of a modified construction.

In the description and claims, the various parts are identified by specific means for convenience, but they are intended to be as generic in their application as the prior art will permit.

Referring to the drawings, the numeral 10 generally designates a time-recorder of usual construction and 11 generally designates a motor-driven timing-and-resetting unit attached to the time-recorder.

The time-recorder 10 has a frame which includes a plurality of frame-plates 12, 13 and 14 suitably connected together by means including pillars 15.

A shaft 16 is rotatably mounted in the frame-plates 12, 13 and 14 of the recorder and has rigidly secured thereto a ratchet-wheel 17 adapted to be engaged by a pawl 18 pivoted on a lever 19 which has its lower end mounted with freedom for rotary movement on the shaft 16. A spring 20 interconnects the pawl 18 and lever 19 to yieldingly hold the pawl in engagement with the teeth of the ratchet-wheel 17. A pivoted holding-pawl 21 is yieldingly engaged with the teeth of the ratchet-wheel 17 by a spring 22. At the left end of Fig. 1, the shaft 16 has a gear-wheel 23 rigidly secured thereto. A gear-wheel 24 rotatably mounted on an arbor 25 is in driven engagement with the gear 23, and in conjunction

with other well-known drive-means serves to drive the time-recording wheels 26, 27 and 28 of the recorder in any usual or well known way.

The gear-wheel 23 on the shaft 16 also is in driving engagement with a gear-wheel 29 thereabove which is rigidly secured to a shaft 30 rotatably mounted in the frame-plates 12 and 13. A gear-wheel 31 rigidly secured to the shaft 30 drives a gear 32 rigidly secured on the minute-arbor 33 which has a usual minute-hand 34 rigidly secured thereto. An hour-hand 35 is secured on an hour-sleeve 36 which can be driven by any usual gearing well known to those skilled in the art. A dial 37 also forms part of the recorder clock.

The motor-driven timing-and-resetting unit 11 has a frame including two plates 38 and 39 secured together in spaced-apart relation by spacing-means including pillars 40. The frame of the motor-driven unit 11 is secured to the frame of the recorder-unit 10 in any suitable way. A shaft 41 is rotatably mounted in the frame-plates 38 and 39 and has a gear-wheel 42 rigidly secured thereto, the gear-wheel 42 being drivable in either of opposite rotary directions by means of a reversible electric motor 43 driving through a train of reduction-gears 44. Also rigidly secured to the shaft 41 is a timing-cam 45 and a reset-cam 46. A driving-cam 47 is mounted for free rotation on the shaft 41 and has a coupling-lug 48 secured on one face thereof adapted to be engaged and driven by a complementary coupling-lug 49 secured on the adjacent face of the reset-cam 46. A shaft 50 is rotatably mounted in the frame-plates 38 and 39 and has secured thereto an arm 51 which has a pawl-shaped end or nose 52 adapted to cause the arm 51 to be swung out by the nose 52 being engaged by each of the cam-faces 53 of the teeth 54 of the cam 47 as the latter is rotated. Any reverse rotation of the cam 47 is prevented by the nose 52 of the arm 50 engaging against one of the locking-faces 55 of the cam 47. Also rigidly secured to the shaft 50 is an arm 56 which has pivoted to its lower end, a link 57 which in turn is pivoted to the lever 19. When the driving-cam 47 is driven counterclockwise (Fig. 2), the successive cam-faces 53 successively swing the lower end of the arm 56 to the left and thus through the link 57 correspondingly swing the lever 19 to the left against the action of the spring 58 which interconnects the lever 19 with any suitable portion of the frame of the recorder 10.

The timing-cam 45 in the particular construction illustrated is so driven by the gearing from the motor 43 that it makes two revolutions per hour, and inasmuch as the cam 45 is provided with thirty cam-teeth 59, each cam-tooth 59 during the rotation of the cam 45 closes the electric-switch contacts 60 of the switch 61 once per min-

ute and breaks these contacts once per minute, as will be hereinafter set forth.

The reset-cam 46 has a time-advancing surface 62, a neutral surface 63 and a time-retarding surface 64. A switch 65 has two spaced-apart contacts 66 and 67, and an intermediate movable contact 68 adapted to be moved into electrical engagement with either contact 66 or 67, depending upon what surface portion of the reset-cam 46 the contact-arm end 69 rests, as will be more fully hereinafter set forth.

The motor 43 (illustrated schematically in Fig. 6) is a Barber Coleman reversible induction motor, which has a power-coil 70 which has one end connected to the line-wire 72 and has the other end connected to switching mechanism adapted to connect with the line-wire 71, as hereinafter set forth, the line-wires 71 and 72 receiving power from any suitable power source such, for example, as a 115-volt alternating electric current, and the motor has two pairs of directional coils 73 and 74. This motor has the characteristic that when the power-coil alone is excited by current from the line-wires 71 and 72, the motor does not run but merely stands still. But when the pair of directional-coils 73 is short circuited on itself, this causes the motor to run in one direction, which causes the clock hands 34 and 35 to rotate clockwise, and when the pair of directional-coils 74 instead of coils 73 is short-circuited on itself, the motor runs in the opposite direction. But if neither of the pairs of the directional-coils are short-circuited, then the motor does not run in any direction.

A usual master clock 75 receives electric current from any suitable source as, for example, from a 115-volt alternating-current source over the wires 76 and 77, which may be from the same source that supplies current to the power-coil of the electric motor. The master clock 75 can be connected by two wires 78 and 79 to a plurality of usual secondary clocks 80 which are adapted to be actuated in timekeeping relation with the master clock as, for example, to be actuated every minute to move their hands forward, and to periodically reset them to correct time, all as is well understood to those skilled in the art.

The wires 78 and 79 also are connected to the coil or coils 81 of an electromagnetic relay 82 having opposite magnetic poles 83 and 84 adjacent which are respectively located armatures 85 and 86. The master clock normally sends a relatively-low voltage current over the wires 78, 79 at intervals of one minute for the timekeeping or timing function, and once an hour sends a higher voltage current over the wires 78, 79 for resetting purposes. The armature 85 of the relay 82 is so constructed that it will be actuated by either the low or the high voltage current through the relay so that at every time a current either of low or high voltage is sent over the wires 78, 79, the armature 85 will be drawn by the pole 83 to cause the armature 85 to engage the electric contact 87 to thus permit current to pass from the line-wire 71 through the armature 85 and across the contact 87 and along the wire 88 to the power-coil 70 of the motor. But the armature 86 is so constructed or biased or spaced from the magnetic pole 84 that it will not be actuated by the lower voltage current applied to the relay, but only by the higher voltage current. The armature 86 is normally engaged with the electric contact 89 to normally close the circuit through the directional coils 73 of the motor 43, and when the armature 86 is attracted by the magnetic pole

84 to cause it to engage the electric contact 90, the circuit of the directional coils 73 is opened by virtue of the armature 86 breaking contact with the contact 89, and the making of contact 5 of the armature 86 with the contact 90 places the middle or neutral contact 91 of the directional coils 73, 74 of the motor 43 in contact with the intermediate electric contact 68 mounted on the spring-arm 69 of the switch 65, so that if the end 10 of arm 69 rests upon the cam-surface 63 as shown in Fig. 6, then neither pair of directional coils 73 or 74 will be short-circuited and the motor 43 will not run in any direction. But if the end of arm 69 rests upon the cam-surface 62, then the contacts 68 and 67 will be closed with the result that the directional-coils 73 will be short-circuited to cause the motor 43 to run in the time-advancing or clockwise direction. Or if the end of arm 69 rests upon the cam-surface 15 64, then the contact 68 will be permitted to spring into engagement with the contact 66 to short-circuit the coils 74 which will result in the motor running in the time-retarding or counterclockwise direction. The cam-surface 63 is made relatively short as it is merely for the purpose of maintaining the contact 68 at neutral position at the fifty-ninth minute so that when the next normal clock-advancing impulse passes through the system, the time mechanisms will be advanced one minute to be just exactly on time. For convenience, the two cams 45 and 46 together may be referred to in the claims as second time-means, and the one-way-driven ratchet-like driving-cam 47 may be referred to as third time-means. It is to be noted that the entire recorder-unit 10, including the hand reset-lever 19, could also be viewed as third time-means.

Operation

40 During normal operation of the time-instrument system, the master clock will at regular intervals such, for example, as each minute of time, send out a time impulse of about one second duration. This time impulse in addition to advancing the hands of each of the secondary clocks 80 one minute, also acts upon the relay 82 to cause the armature 85 to close the contact 87 which causes electric power from the wires 71, 72 to energize the power-coil 70 of the motor 43, and since the pair of directional-coils 73 of the motor is short-circuited on itself through the contact 89 and armature 86, this causes the motor 43 to start rotating in the timekeeping or clockwise direction with the consequence that the 45 finger 92 of the switch 61 is caused to ride up one of the inclined surfaces of a cam-tooth 59 of the timing-cam 45 to thus close the contacts 60 of the switch 61 so that the motor 43 continues to have power supplied to its power-coil 70 so that the motor 43 continues to run even after the timing impulse from the master clock has ceased and has permitted the armature 85 to swing away from the contact 87. The motor continues to operate until the finger 92 again descends into a notch between two teeth 59 of the timing-cam 45, whereupon the contacts 60 again open, thus stopping the motor 43. As the ratchet-like driving-cam 47 has the same number of cam-teeth as the timing-cam 45, each time the mechanism causes the timing-cam 45 to rotate a distance of one tooth as just described, the driving-cam 47, by virtue of engagement of the coupling-lugs 48 and 49, will rotate a distance of one tooth and cause a cam-face 53 of a tooth 54 to swing the arm 51, link 57, lever 19 and the connected parts hereto- 50 55 60 65 70 75

fore fully described, to result in the hands 34, 35 of the clock being advanced one minute and in the printing-wheels 26, 27 and 28 also being advanced one minute of time.

When the master clock 75 reaches the fifty-ninth minute, a higher voltage current is sent out over the wires 78 and 79 to reset the secondary clocks and also to so actuate the relay 82 and the associated mechanism to properly reset the second time-means which includes the cams 45 and 46, and the third time-means 47, as hereinbefore mentioned, which will now be fully set forth. The higher voltage reset electric impulse that is sent over the wires 78 and 79 is a long impulse which may, for example, be of twenty seconds duration, and which in any event will be well under one minute and ordinarily under one half-minute in duration, so as to complete the resetting operation in ample time not to interfere with the next minute-interval timing- or timekeeping impulse. If the shaft 41 and the cams 45, 46 and 47 are in slow-time position, then the finger or end of contact-arm 69 will be resting upon the time-advancing surface 62 of the reset-cam 46, thus closing the contacts 68 and 67. And as the higher-voltage current through the relay 82 will draw both the armatures 85 and 86 in toward their respective poles 83 and 84 to close the armatures 85 and 86 respectively with the contacts 87 and 90, this will supply power to the power-coil 70 of the motor 43 and will short-circuit the directional-coils 73 of the motor to cause the motor to rotate in a direction to advance the time position of the shaft 41 and the cams 45, 46 and 47 until the end of arm 69 comes to rest upon the cam-surface 63 of cam 46 which causes the contact 68 to move to neutral position which stops the rotation of the motor 43 and all associated parts, which action occurs upon the fifty-ninth minute so that at the next minute impulse the time mechanisms are advanced to the sixty-minute or upright position and are all at correct time-indicating or timing position.

But if instead of the cam 46, and associated parts, having been slow, it has been fast at the time of the reset impulse coming from the master clock then the time-retarding cam-surface 64 will be in engagement with the arm 69, which will result in contacts 68 and 66 being closed, with the consequence that the directional-coils 74 will be short-circuited instead of coils 73, thereby causing the motor to run in the backward or time-retarding direction which will cause the shaft 41 and the cams 46 and 45 to rotate backward until the cam-surface 63 comes beneath the finger 69 which causes the contact 68 to be moved to neutral position which breaks the circuit in coils 74 and causes the electric motor to be stopped with the time mechanisms in the fifty-ninth minute position awaiting the sixtieth-minute timing-impulse which will place them all on proper time. It will be noted, however, that when the shaft 41 and cams 45 and 46 have been run backward, the cam 47 has not been run backward inasmuch as the coupling-lug 49 will have been moved away from the coupling-lug 48, thus leaving the cam 47, and hands 34 and 35 and the printing-wheels 26, 27 and 28 of the recorder, in their incorrect fast position, but inasmuch as the cam 46 and the shaft 41 and related parts will now be rotated forward in timing or timekeeping movement once per minute by the minute impulses from the master clock acting in a manner hereinbefore set forth, the reset-cam 46 with its coupling-lug 49 will be advanced step-by-step

once per minute until the coupling-lug 49 again engages the coupling-lug 48 on the one-way-driven driving-cam 47. The driving-cam 47, and in consequence the associated parts including the clock-hands 34 and 35 and the printing-wheels 26, 27 and 28 of the recorder, will therefore again start moving forward in correct time owing to the hereinbefore described driving action between the coupling-lugs 49 and 48.

Referring to the modified form of the invention illustrated in Fig. 7, the mode of action is essentially the same as that described concerning the construction illustrated in Fig. 6 except that instead of a two-wire system interconnecting the master clock 75a and the secondary clocks 80a, a three-wire system including the three wires 93, 94 and 95 are employed, these three wires also extending to the relay-means which, in this instance, is formed by two separate relay elements. The two wires 93 and 94 are used to send the timekeeping impulses to the secondary clocks 80a and to the relay 82a, and the two wires 93 and 95 are used to send the hourly reset impulses to the secondary clocks 80a and to the relay 82b. Thus the relay element or relay 82a by acting on the armature 85a serves to pull it into engagement with the contact 87a to cause current from the line-wires 71 and 72 to pass through the power-coil 70 of the motor 43, the directional-coils 73 of the motor being closed through the contact-bar 96 carried by the armature 85b, the mode of operation of the construction illustrated in Fig. 7 being otherwise identical with the mode of operation of the construction illustrated in Fig. 6, during the normal timing operation. When re-setting current is sent out from the master clock through the two wires 93 and 95 to the relay 82b, the armature 85b is pulled to the left, causing the contact-bars 96 and 87 to respectively engage the contacts 87b and 89b. The contact 87b now performs the function of the contact 87a which the contact 87a of the relay element 82a performed at the minute-impulse times to energize the power-coil 70 of the motor 43, and the contact 89b acts in a similar fashion to the contact 89 of the relay 82 illustrated in Fig. 6, in conjunction with the cam-surfaces 62, 63 and 64 and the contact parts 66, 67, 68 and the arm 69 to short-circuit one or the other or neither of directional-coils 73, 74 of the motor 43 to cause the motor to run in one direction or the other or not to run at all in exactly the same manner as has heretofore been fully set forth in the description of the construction illustrated in Fig. 6.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An electric time-instrument system including: master time-means; second time-means; third time-means; electric motor-means adapted to drive said second time-means in either of forward or backward directions; said second time-means when it moves forward in normal timing movement, driving said third time-means forward in timing movement, but when said second time-means moves backward in time-receding movement, it does not drive said third time-means in

any direction, and when said second time-means again moves forward, it does not drive said third time-means forward until said second time-means has moved forward a distance equal to its previous backward time-receding movement; and electric relay-means adapted to be energized by said master time-means to initiate forward timing movement of said motor-means, the said relay-means also being adapted to be energized by said master time-means to initiate either forward time-advancing or backward time-retarding reset-movement of said motor-means, depending on whether said second time-means is slow or fast.

2. An electric time-instrument system including: master time-means; second time-means including switch-mechanism; third time-means; electric motor-means adapted to drive said second time-means in either of forward or backward directions; said second time-means when it moves forward in normal timing movement, driving said third time-means forward in timing movement, but when said second time-means moves backward in time-receding movement, it does not drive said third time-means in any direction, and when said second time-means again moves forward, it does not drive said third time-means forward until said second time-means has moved forward a distance equal to its previous backward time-receding movement; and electric relay-means adapted to be energized by said master time-means to initiate forward timing movement of said motor-means, the said relay-means also being adapted to be energized by said master time-means to initiate either forward time-advancing or backward time-retarding reset-movement of said motor-means, depending on whether said second time-means is slow or fast; the movement of said second time-means actuating its switch-mechanism which causes said motor-means to continue the forward timing movement initiated by said relay-means during a predetermined distance of movement of said second time-means, whereupon said second time-means actuates said switch-mechanism to cause said motor-means to stop.

3. An electric time-instrument system including: master time-means; second time-means which includes timing-movement cam-means and switch-mechanism therefor, and reset-movement cam-means and switch-mechanism therefor; third time-means; electric motor-means adapted to drive said second time-means in either of forward or backward directions; said second time-means when it moves forward in normal timing movement, driving said third time-means forward in timing movement, but when said second time-means moves backward in time-receding movement, it does not drive said third time-means in any direction, and when said second time-means again moves forward, it does not drive said third time-means forward until said second time-means has moved forward a distance equal to its previous backward time-receding movement; and electric relay-means adapted to be energized by said master time-means to initiate forward timing movement of said motor-means; the movement of said timing-movement cam-means actuating its switch-mechanism which causes said motor-means to continue the forward timing movement initiated by said relay-means during a predetermined distance of

movement of said timing-movement cam-means, whereupon the latter actuates its switch-mechanism to cause said motor-means to stop; the said relay-means also being adapted to be energized by said master time-means to cause said reset-movement cam-means and its switch-mechanism to cause either forward time-advancing or backward time-retarding reset-movement of said motor-means, depending on the position of said reset-movement cam-means.

4. An electric time-instrument system including: master time-means; second time-means; third time-means; a reversible electric motor adapted to drive said second time-means in either of forward or backward directions; said second time-means when it moves forward in normal timing movement, driving said third time-means forward in timing movement, but when said second time-means moves backward in time-receding movement, it does not drive said third time-means in any direction, and when said second time-means again moves forward, it does not drive said third time-means forward until said second time-means has moved forward a distance equal to its previous backward time-receding movement; and electric relay-means adapted to be energized by said master time-means to initiate forward timing movement of said motor, the said relay-means also being adapted to be energized by said master time-means to initiate either forward time-advancing or backward time-retarding reset-movement of said motor, depending on whether said second time-means is slow or fast.

5. An electric time-instrument system including: master time-means; second time-means which includes timing-movement cam-means and switch-mechanism therefor, and reset-movement cam-means and switch-mechanism therefor; third time-means; a reversible electric motor adapted to drive said second time-means in either of forward or backward directions; said second time-means when it moves forward in normal timing movement, driving said third time-means forward in timing movement, but when said second time-means moves backward in time-receding movement, it does not drive said third time-means in any direction, and when said second time-means again moves forward, it does not drive said third time-means forward until said second time-means has moved forward a distance equal to its previous backward time-receding movement; and electric relay-means adapted to be energized by said master time-means to initiate forward timing movement of said motor; the movement of said timing-movement cam-means actuating its switch-mechanism which causes said motor to continue the forward timing movement initiated by said relay-means during a predetermined distance of movement of said timing-movement cam-means, whereupon the latter actuates its switch-mechanism to cause said motor to stop; the said relay-means also being adapted to be energized by said master time-means to cause said reset-movement cam-means and its switch-mechanism to cause either forward time-advancing or backward time-retarding reset-movement of said motor, depending on the position of said reset-movement cam-means.

WALTER W. LUNDEN.
